LOUIS A. PARADISE AND WILBUR J. COULTAS, OF MOLINE, ILLINOIS, ASSIGNEES TO
DEERE & COMPANY, OF MOLINE, ILLINOIS, A CORPORATION OF ILLINOIS

CORN PICKER

Application filed May 28, 1927. Serial No. 194,883.

The present invention relates to corn picking machines designed for picking the ears of standing corn and husking these ears as a continuous operation; and it has as its general object to provide an improved construction of wheeled frame for this type of machine.

In the particular construction of machine to which our invention has reference, the picker mechanism which picks or snaps the ears from the standing corn is disposed at one side of the frame, and the husking mechanism which husks or shucks the ears is disposed at the opposite side of the frame. Each of these mechanisms has a considerable overhang at the sides of the machine, with the principal weight of each concentrated at points located outwardly beyond the planes of the two load bearing wheels. As a result of this construction the weight of each of the aforesaid mechanisms has a lateral fulcrum action about the plane of its adjacent wheel, thereby creating stresses in the frame which tend to buckle the same upwardly at its center. One of the features of the invention is to provide a frame which is so constructed as to be amply reinforced against such bending or buckling stresses. Another feature of the invention is to construct this frame so that all tendency of a parallelogram motion between the frame members is avoided. Another feature is to reinforce the frame against any distorting effect of the draft forces applied to the frame.

Referring to the accompanying drawings wherein we have illustrated the preferred embodiment of our invention:

Fig. 1 is a plan view of the present corn picker;

Fig. 2 is a perspective view of the wheeled frame, with which our invention is principally concerned;

Fig. 3 is a plan view of this frame;

Fig. 4 is a transverse sectional view through the machine, for the purpose of illustrating the overhang of the picker and husking mechanisms; and

Fig. 5 is a longitudinal sectional view through the frame on the inner side of one

of the wheels, showing the arched reinforcing trusses.

Referring to Fig. 1, it will be seen that the picker mechanism, which has been designated 8 in its entirety, extends longitudinally of the machine at one side thereof. The husking mechanism, which has been designated 9 in its entirety, is also disposed longitudinally of the machine, at the opposite side thereof. The details of each of these mechanisms form no part of the invention, and their general construction and arrangement is well known. It will, therefore, suffice to say that the picker mechanism comprises the usual gathering members 11-11, for guiding the stalks into the machine, and a pair of inclined snapping rolls 12-12 (Fig. 4), which snap or pick the ears from the stalks. The husking mechanism 9 comprises any suitable arrangement of inclined husking rolls 13-13, which strip the husks, silks, et cetera, from the ears as the latter travel down along the upper surfaces of the rolls. The picked ears are conveyed from the picker mechanism 8 to the husking mechanism 9 by any well known type of elevator 14. These machines are usually provided with other complementary devices, such as a wagon elevator 15 for conveying the husked ears up to a point for dumping into a wagon, and a husk conveyor 16 operating beneath the husking rolls for carrying the husks and refuse back to a point of discharge at the rear of the machine, all of which is well known. The power for driving the several operating units may be derived from a motor mounted on the picking machine, or from a power take-off from the tractor, or the traction power of the load bearing wheels of the picking machine may be utilized to drive these operating devices, such drive forming no part of the invention.

The operating parts of the machine are all supported on a main frame 18 in which are journaled the two load bearing wheels 19. As shown in Fig. 4, these two wheels are set inwardly from the sides of the machine, such being desirable for giving the desired clearance for mounting the picker and the husking mechanisms. As before re-

marked, this arrangement results in both mechanisms having an overhang at the sides of the machine. Referring now to the construction of the main frame, as best shown in Figs. 2 and 3, it will be seen that it is of rectangular form and comprises two longitudinally extending angle bars 21-22, disposed between the wheels 19, and two transversely extending angle bars 23 and 24 at the front and rear ends of the frame. A third cross-bar 25 is provided in back of the rear cross-bar 24. The two longitudinal frame bars 21 and 22 are riveted or bolted to the three cross-bars, as indicated at 26. Each of these several frame bars is preferably of angle section, and the longitudinally extending bars are disposed with their angles facing upwardly and the transversely extending bars with their angles facing downwardly. The end bar 25 may be provided with additional points of attachment to the bar 24, such as by the provision of one or more short connecting bars 27.

The wheels 19 are journaled on a transversely extending axle 28 which is disposed substantially centrally between the front and rear cross-bars 23 and 24. Bearing brackets 29, which are bolted to the longitudinal frame bars at 31, secure the axle to these bars. The axle is held against rotation, and the wheels 19 have journal mounting on anti-friction roller bearings carried by the axle. Extending inwardly from each of these roller bearings is a bearing collar 32 which is held against rotation by providing the same with one or more notches which receive lugs 33 projecting from the end of the adjacent bearing bracket 29. We have shown the wheels 19 as being provided with sprocket wheels 34, corresponding to a construction wherein the operating parts of the machine are driven by traction power, but any of the other forms of power drive may, of course, be employed instead of this traction drive.

Mounted on the outer ends of the axle 28 are sleeve-like brackets or hubs 35 which are rigidly pinned or keyed to the axle. Extending upwardly from these brackets are webs 36 to which are bolted inverted L-shaped brackets 37 and 38 for attachment to the picker mechanism and to the husking mechanism respectively, as will be presently described. Projecting laterally from the end of each hub bracket 35 are lugs or ears 39-39 for effecting bolting attachment to outer frame bars 41. These frame bars incline inwardly from the bracket hubs and have inwardly bent ends 42 which are bolted or riveted to the vertical flanges of the transverse frame bars 23 and 24. It will be observed that such outer frame bars join the axle to the frame on both sides of each wheel, corresponding to a wheelbarrow mounting of each wheel. The bars 41 resist fore and aft stresses at the ends of the axle and also carry

stresses tending to rotate the bracket hubs 35 on the axle.

The draft force is applied to the front frame bar 23 at a plurality of spaced points along its length, such points of draft connection being represented by the three pivot eyes 43 which are secured to the bar 23. Two of these pivot eyes are preferably disposed in alignment with the longitudinal frame bars 21 and 22, and the third pivot eye is preferably mounted adjacent to the picker side of the frame. The draft frame which has pivotal connection with the eyes 43, is indicated at 44 in Fig. 1, such draft frame having mounting on a tongue truck or being adapted for connection directly to a tractor.

Referring to Fig. 4, the picker mechanism 8 comprises any suitable construction of supplementary frame on which the gathering arms and the picker rolls have mounting, such supplementary frame being represented by the two inclined angle bars 45 and the two horizontal angle bars 46. These angle bars are suitably joined together by other frame bars, one of which is indicated at 47, extending transversely of the horizontal bars 46. The inverted L-shaped bracket 37 which rises from the end of the axle 28, has its upper arm bolted to the bar 47, as indicated at 48. The forward portion of this picker frame is also bolted to the front bar 23 of the main frame, it being noted that the adjacent end of said bar is turned to incline downwardly, as indicated at 49, for fastening to one of the inclined bars 45. The rear end of the picker frame may also be connected to the main frame by an inclined bar (not shown) extending between the ends of the horizontal bars 46 and the main frame bar 25.

The husking mechanism 9 comprises any suitable frame structure represented by the side boards 52, 53 and the angle plates 54, which are joined by one or more transversely extending bars 55. The inverted L-shaped bracket 38 at this side of the machine is fastened to the frame of the husking mechanism, preferably being bolted to the transverse frame bar 55, as indicated at 56. The front and rear ends of the husking mechanism are also secured to the front and rear bars 23 and 24 of the main frame by inclined braces or bars (not shown) which extend diagonally down from the supplementary frame of the husking mechanism to said main frame bars 23 and 24.

It will be observed from the foregoing arrangement that the major portion of the weight of each of the picking and husking mechanisms 8 and 9 is disposed in a vertical plane located outwardly beyond the plane of the adjacent side wheel 19. Thus, this weight in each instance, has a fulcrum action around the lower tread point of the adjacent wheel, tending to create upwardly acting buckling stresses in the intermediate portion of the

frame between the wheels. It will also be noted that because of the long forward extension of the gatherer arms 11 and picker rolls 12 beyond the front end of the main frame, which parts engage the corn row, this corner of the frame is subjected to stresses tending to warp the same downwardly. The through axle 28 serves to reenforce the frame to a limited extent against the buckling stress, but is inadequate to carry all of the stress. To the end of reenforcing the frame against all of its loads we have provided two arched trusses or reenforcing bars 58 and 59 each of which has connection with the intermediate point of the axle and with the side portions of the frame. Secured to the center of the axle is a heavy bearing member 61, from the upper side of which rises a diagonal bracket 62. Extending from the rear of this bearing at a relatively low point is a second bracket portion 63. The upper truss bar 58 extends diagonally of the frame and is arched to pass over the upper bracket 62, to which the bar is rigidly bolted at 64. The downwardly inclined rear end of the truss bar is riveted or bolted to the inner frame bar 21 and to the rear cross bar 24 at the husking side of the machine as indicated at 26'. The arch of this truss bar continues forwardly for passing over the upper side of the other longitudinal frame bar 22, to which the truss bar is rigidly secured through an angle bracket 66, the truss bar being bolted to such bracket at 67 and the latter being bolted to the longitudinal frame bar at 68. The front end of the truss bar inclines downwardly and is bolted or riveted to the front frame bar 23 at 69, adjacent to the corner which carries the forward overhang of the picker mechanism.

The lower truss bar 59 extends transversely between the inner frame bars 21-22 and has its central portion arched downwardly to pass under the lower bracket extension 63, to which the bar is rigidly bolted at 71. The upwardly inclined outer ends of the truss bar 59 are fastened to the under sides of the longitudinal frame bars 21-22, such as by the bolts 31 which secure the bearing brackets 29 in place.

By virtue of the fact that the arched portions of the two trusses have strut support with the intermediate portion of the axle at points spaced upwardly and downwardly from the horizontal plane of the frame, such trusses form substantial reenforcing means for carrying the buckling stresses set up in the center of the frame, the upper truss 58 acting in tension and the lower truss in compression. The forward reach of the diagonal truss to that corner of the frame which carries the forward overhang of the picker mechanism also reenforces this corner against the warping stresses referred to, the bracket 66 constituting a fulcrum point of reaction for carrying such stresses. Finally, it should be noted that the diagonal truss reenforces the several members of the frame against draft or other stresses which might tend to cause parallelogram motion between the frame bars.

What we claim as our invention and desire to secure by Letters Patent, is—

1. In a corn picker, the combination with corn picking and husking mechanisms, of a main frame, two side wheels for said frame, an axle for said wheels fixedly secured to said frame to transversely brace the latter, each of said mechanisms being supported on said main frame with the major portion of the weight of each disposed outwardly beyond the plane of the adjacent side wheel, and an arched truss having its intermediate portion connected to said axle and having its ends connected to the side portions of said frame for reenforcing said frame against buckling stresses.
2. In a corn picker, the combination with corn picking and husking mechanisms, of a main frame, two side wheels for said frame, each of said mechanisms being supported on said main frame with the major portion of the weight of each disposed outwardly beyond the plane of the adjacent side wheel, and two arched trusses, one acting in compression and the other in tension, for reenforcing the intermediate portion of said frame against buckling stresses.
3. In a corn picker, the combination with corn picking and husking mechanisms, of a wheeled frame for supporting said mechanisms, said frame comprising a rectangular arrangement of longitudinal and transverse frame bars connected with the axle of the wheels, and a diagonally extending reenforcing member for bracing said frame bars against parallelogram motion, said member being connected intermediate its ends with said axle.
4. In a corn picker, the combination with corn picking and husking mechanisms, of a main frame on which each of said mechanisms have overhanging support at the opposite sides thereof, an axle secured to said frame, side wheels mounted on said axle, and an arched brace connected to the intermediate portion of said axle and to portions of said frame spaced laterally therefrom for trussing said frame and axle against buckling stresses.
5. In a corn picker, the combination with corn picking and husking mechanisms, of a main frame on which each of said mechanisms have overhanging support at the opposite sides thereof, said frame comprising longitudinal and transverse frame members, an axle secured to said longitudinal frame members, side wheels on said axle, a bracket carried by the intermediate portion of said axle, and an arched truss connected to said bracket and to portions of said frame spaced laterally therefrom for trussing the center

- of said frame and of said axle against buckling stresses.
6. In a corn picker, the combination with corn picking and husking mechanisms, of a frame on which each of said mechanisms have overhanging support at the opposite sides thereof, said frame comprising longitudinal and transverse frame members, an axle secured to said longitudinal frame members, side wheels on said axle, a bracket carried by the intermediate portion of said axle between said longitudinal frame members, an arched truss extending diagonally of said longitudinal frame members and having its intermediate portion secured to said bracket, and a second arched truss extending transversely of said longitudinal frame members and having its intermediate portion secured to said bracket.
7. In a corn picker, the combination with corn picking and husking mechanisms, of a main frame on which each of said mechanisms have overhanging support at the opposite sides thereof, said frame comprising a pair of inner frame bars and a pair of outer frame bars, an axle having its ends secured to said outer bars and being connected intermediate its ends to said inner bars, wheels mounted on said axle between the inner and outer bars at each side of the frame, and truss means connecting the center of said axle with said inner frame bars for trussing said frame against buckling stresses.
8. In a corn picker, the combination of a main frame comprising two inner longitudinally extending frame bars, two outer longitudinally extending frame bars, front and rear transverse bars connected to said longitudinally extending bars, a transversely extending axle secured to both pairs of said longitudinally extending frame bars, wheels journaled on said axle between the inner and outer bars at each side of said frame, a corn picking mechanism at one side of said frame disposed outwardly beyond the plane of the adjacent side wheel, a corn husking mechanism at the opposite side of said frame disposed outwardly beyond the plane of the other side wheel, each of said corn picking and husking mechanisms comprising a supplementary frame, means for supporting each of said supplementary frames on said main frame comprising inverted L-shaped brackets secured to said supplementary frames, bracket hubs mounted on the ends of said axle and connected to said brackets, a bearing member mounted substantially on the center of said axle, a strut projecting upwardly from said bearing member, an arched truss bar extending diagonally between said inner longitudinal frame bars and having its intermediate portion secured to said strut, and a downwardly arched truss bar extending transversely of said longitudinal frame bars and having its intermediate portion secured to said bearing member.
9. In a corn picker, the combination with corn picking and husking mechanisms, of a wheeled frame having a wheel axle rigidly secured thereto, said mechanisms each being supported on said frame in a position overhanging the opposite sides thereof, and means connected with said frame and extending diagonally thereof, said means being rigidly connected with said axle and cooperating therewith to brace the intermediate portion of said frame against the stresses set up therein by the overhanging support of said mechanisms.
10. In a corn picker, the combination with corn picking and husking mechanisms, of a frame on which each of said mechanisms have overhanging support on the opposite sides thereof, said frame comprising longitudinal and transverse frame members, an axle secured to said longitudinal frame members, side wheels on said axle, a bracket carried by the intermediate portion of said axle between said longitudinal frame members, an arched truss extending diagonally of said longitudinal frame members and having its intermediate portion secured to said bracket, a second arched truss extending transversely of said longitudinal frame members and having its intermediate portion secured to said bracket, and bar members connected to said transverse frame members and extending substantially parallel to the longitudinal frame members, said bar members being connected to the axle to brace the ends thereof against bending, and said bracket securing the intermediate portion of said axle against buckling.
11. In a corn picker, the combination with corn picking and husking mechanisms, of a main frame on which said mechanisms are mounted on opposite sides thereof, side wheels for said frame, axle means for said wheels, brackets on said axle means for further supporting said mechanisms, and means connected with said axle means and with said frame at points fore and aft of said wheels to strengthen said axle means against bending stresses.
12. In a corn picker, the combination with corn picking and husking mechanisms, of a main frame on which said mechanisms are mounted on opposite sides thereof, side wheels for said frame, axle means for said wheels, brackets rigidly fixed to said axle means for further supporting said mechanisms, and means rigidly fastened to said axle means for connecting the latter with said frame at points fore and aft of said wheels to resist torsional and bending stresses in said axle means.
13. In a corn picker, the combination with corn picking and husking mechanisms, of a main frame on which said mechanisms are

mounted on opposite sides thereof, side wheels for said frame, axle means for said wheels, brackets rigidly fixed to said axle means for further supporting said mechanisms, and means rigidly fastened to said axle means for connecting the latter with said frame at points fore and aft of said wheels to resist torsional and bending stresses in said axle means, said fastening means being adapted to hold the brackets against rotation relative to said axle means.

14. In a corn picker, the combination with corn picking and husking mechanisms, ground wheels supporting an axle, a frame on said axle for supporting said mechanisms, and a diagonally extending reinforcing member having its ends connected with said frame to brace it against weaving and buckling, said member being rigidly connected intermediate its ends with said axle.

15. In a corn picker, the combination with corn picking and husking mechanisms, ground wheels supporting an axle, a frame on said axle for supporting said mechanisms, a diagonally extending brace connected with said frame to prevent weaving and buckling thereof, and a casting secured to said brace intermediate its connections with the frame and embracing said axle.
